[57] CLAIM

The ornamental design for a container for liquids, as shown and described.

DESCRIPTION

FIG. 1 is a perspective view of a container for liquids showing my new design;

FIG. 2 is a top view;

FIG. 3 is a side elevational view the opposite side being a mirror image thereto except for the conventional screw threading on the bottle neck;

FIG. 4 is a bottom view;

FIG. 5 is an end view of one end of the container showing the bottom horizontal grip; and,

FIG. 6 is an end view of the other end of the container showing the main shoulder grip.
